UNITED STATES PATENT OFFICE.

JOHN D. MAUCH AND FRANK MARTIN, OF RIB LAKE, WISCONSIN.

MEANS FOR SUPPORTING AND RELEASING RETAINING-STAKES.

1,083,118.

Specification of Letters Patent. Patented Dec. 30, 1913.

Application filed October 8, 1913. Serial No. 794,068.

To all whom it may concern:

Be it known that we, JOHN D. MAUCH and FRANK MARTIN, citizens of the United States, and residents of Rib Lake, in the 5 county of Taylor and State of Wisconsin, have invented a new and Improved Means for Supporting and Releasing Retaining-Stakes, of which the following is a full, clear, and exact description.

10 Our invention has reference to devices for supporting and releasing retaining stakes; and the object thereof is to provide a simple, strong, inexpensive and safe device that can be easily secured to the bolsters of a car.

15 We attain the above object by providing a casing having means whereby it can be secured to the bolster of a car, and which is provided with a bolt having locking means.

20 A shoe which carries the stake has means adapted to engage the casing and to be secured by the bolt to the casing, with the locking means preventing the accidental displacement of the shoe from the casing.

25 The invention consists of the construction and combination of parts to be more fully described hereinafter and fully set forth in the claims.

30 Reference is to be had to the accompanying drawings forming a part of this specification, in which like characters indicate corresponding parts in all the views and in which:

35 Figure 1 is a side elevation of an end of a railway car provided with an embodiment of our invention; Fig. 2 is a section on line 2—2, Fig. 1, with certain parts broken away to show the details of construction; Fig. 3 is a plan view of Fig. 1; Fig. 4 is a section on line 4—4, Fig. 3; Fig. 5 is an end view on 40 Fig. 4, in the direction of the arrow, with the shoe removed; and Fig. 6 is a perspective view of the shoe.

45 Referring to the drawings, 7 represents one end of a flat car having the customary bolsters 8. One end of each of the bolsters on the same side of the car receives a fixed shoe 9. The opposite end of the bolster receives a U-shaped casing 10, the bottom of which is provided with longitudinal slots 50 11 extending parallel to the sides of the U member. The sides of the member 10 are provided with means by which the same are secured to the bolster. Each of the sides of the U-shaped casing 10 is provided with a slot 12, alining with each other, and through which passes a bolt 13 having

notches 14 spaced from each other so as to register with the slots 11 provided in the base of the U-shaped casing 10. The bolt 13 is also provided with pins 15 and 16 adjacent each end of the bolt and whereby the movement of said bolt in the casing is limited. The pin 15, when contacting with the side of the casing, brings the notches 14 in register with the slots 11.

60 The end of the bolster contacting with the base of the casing 10 is cut away so as to allow the bolt 13 to move freely; also recesses 17 are formed in the bolster opposite the slots 11. A U-shaped shoe 18 is provided at each side with a hook-shaped extension 19. The extension 19 of the shoe passes through the slots 11 inside the recesses 17 of the bolster when the bolt 13 is in position, as shown in Fig. 5. By moving 65 the bolt 13 so that the pin 16 contacts with the adjacent side, the shoe 18 is locked to the casing 10. To prevent the shoe 18 from disengaging itself accidentally from the casing 10, a locking member 20 is pivotally 70 secured to the side of the casing 10 where the pin 15 is provided; and the width of the member 20 is such as to fit with its extension 21 between the pin and the side when the pin is in the position shown in dotted 75 line in Fig. 5.

80 The shoe 18 is preferably connected to the bolster 8 by means of a chain 22, the purpose of which will appear hereinafter. The shoes 9 and 18 are each adapted to receive 85 stakes 23. When a load is carried between said stakes on the car, and it is desired to discharge the same, the stakes 23 are made to collapse by causing the extension 21 of the locking member 20 to retract to the position shown in dotted line in Fig. 2, thereby 90 permitting the bolt 13 to move from the position shown in dotted line in Fig. 5 to the position shown in full by forcing the same with any suitable means. This will permit 95 the shoe 18 to drop out from the casing 10 under the action of the load, and the chain securing the shoe to the bolster will prevent the same from being crushed by the falling load.

100 To operate simultaneously the two bolts 13 of the two devices secured to the adjacent bolsters 8, we provide a sliding bar 24 intermediate said bolts. The sliding bar 24 is mounted in bearings 25 secured to the 105 platform of the car; and the ends of said sliding bar bear against the ends of the bolt,

so that when bolt 13, at the left end of the device, is forced, the bolt 13 of the right end of the device is forced to move with it by the medium of the sliding bar 24. It is understood that the locking members 20 are placed in the position shown in dotted line, Fig. 2.

Having thus described our invention, we claim as new and desire to secure by Letters 10 Patent:

- 15 1. In a device of the class described,—a U-shaped casing having slots in the base; a shoe adapted to carry a stake having extensions adapted to engage said slots; a bolt in the casing adapted to engage said extensions and thereby secure said shoe to the casing; and locking means for said bolt to prevent accidental disengagement of said shoe and casing.
- 20 2. In a device of the class described,—a U-shaped casing having slots in the base thereof and alining slots in the sides thereof adjacent the base; a bolt engaging said side slots and having notches adapted to register 25 with the slots in the base; means for limiting the movement of the bolt in the base; a U-shaped shoe having hook-shaped extensions at the sides thereof, said shoe being adapted to engage the slots in the base of

the casing with said extension when the 30 notches of the bolt are registering with the slots in the base of the casing, said bolt locking said shoe to the casing when its slots are not registering with the slots in the base; and locking means associated with the 35 casing and the means limiting the movement of the bolt, whereby said shoe is prevented from accidental displacement from said casing.

3. In a device of the class described, a 40 U-shaped casing having slots in the base, a shoe adapted to carry a stake having extensions adapted to engage said slots, a bolt in the casing adapted to engage said extensions and thereby secure said shoe to the 45 casing, said bolt having means whereby it will disengage the shoe from the casing, and locking means for said bolt to maintain the same in a position such as to lock said shoe to the casing.

In testimony whereof we have signed our names to this specification in the presence of two subscribing witnesses.

JOHN D. MAUCH.
FRANK MARTIN.
